UNITED STATES PATENT OFFICE.

JAMES CANTRY ALEXANDER, OF FORT MITCHELL, ALABAMA.

PORTABLE FENCE.

SPECIFICATION forming part of Letters Patent No. 644,564, dated March 6, 1900.

Application filed October 27, 1899. Serial No. 735,000. (No model.)

To all whom it may concern:

Be it known that I, JAMES CANTRY ALEXANDER, a resident of Fort Mitchell, in the county of Russell and State of Alabama, have 5 invented certain new and useful Improvements in Portable Fences; and I do hereby declare the following to be a full, clear, and exact description of the invention, such as will enable others skilled in the art to which

10 it appertains to make and use the same.

My invention relates to an improvement in portable fences, one object of the invention being to so construct a series of panels or sections of fence that they can be readily secured together in position to form a fence and which can be readily separated and removed and conveyed from place to place.

A further object is to provide a portable fence with improved means for securing the 15 same in place and which can be packed in a small space for shipment.

With these objects in view the invention consists in certain novel features of construction and combinations and arrangements of parts, as will be more fully hereinafter described, and pointed out in the claims.

In the accompanying drawings, Figure 1 is a view in elevation, illustrating my improvements; and Figs. 2, 3, and 4 are detail views.

30 A A represent a series of panels or fence-sections, each consisting of a pair of parallel uprights 1 at each end and a series of rails 2, connecting said uprights and secured at their ends between uprights of the respective pairs.

35 Transversely-disposed blocks 3 are secured to the uprights, below the lowest rail 2, to form supports for the panel or fence-section, each block being notched for the accommodation of the lowest rail.

40 Vertical parallel bars 4 are secured to the rails 2 near their central portions, and said vertical bars are connected at their upper and lower ends by means of cross-bars 5, said bars 4 and 5 thus forming a pocket for the reception

45 of a flat post 6, adapted to be driven into the ground to assist in supporting each fence-section or panel. The rails 2 project between the uprights 1 only about half the width of the latter, and when two sections of fence are

50 placed end to end a passage will be formed

for the reception of flat post 7, which is driven into the ground, and, together with the posts 6, heretofore referred to, will securely hold the sections of fence together and anchor them to the ground. One upright of each 55 pair of parallel uprights 1 is preferably made longer than the other, and a wire 8 is secured at its ends to said longer uprights, thus completing a most attractive fence.

It will be seen that when it is desired to 60 move the fence from one place to another it is simply necessary to pull up the posts 6 and 7, when the sections or panels A can be placed side by side and if shipped in a wagon can be placed in an upright position, supported 65 on the blocks 3, and hence occupy but a small space.

Various slight changes might be resorted to in the general form and arrangement of the several parts described without departing 70 from the spirit and scope of my invention, and hence I would have it understood that I do not wish to limit myself to the precise details set forth, but consider myself at liberty to make such slight changes and alterations 75 as fairly fall within the spirit and scope of my invention.

Having fully described my invention, what I claim as new, and desire to secure by Letters Patent, is—

1. A portable fence comprising several abutting sections, each section comprising several parallel rails, two parallel uprights secured at each end of the series of rails and projecting at their outer vertical edges beyond said rails, the parallel uprights of one section abutting against the parallel uprights of the adjacent section so as to form a pocket between the two sections, and posts inclosed and guided in said pockets throughout the 85 lengths of the latter and adapted at their lower ends to be driven into the ground.

2. A fence comprising a series of portable sections, each section having parallel uprights projecting at their edges beyond the 95 body of the section to which they are secured, the uprights of adjacent sections abutting and forming pockets at the juncture of the sections, posts passing through and guided in said pockets, bars secured to and project- 100

ing laterally beyond the lower end of said uprights, parallel guide-bars secured to the central portion of each section, posts disposed between and guided by said parallel bars and 5 cross-bars secured to the outer faces of said parallel bars at the respective ends thereof to prevent outward displacement of said posts.

In testimony whereof I have signed this specification in the presence of two subscribing witnesses.

JAMES CANTRY ALEXANDER.
